UNITED STATES PATENT OFFICE

JOHN J. PETERS, OF NEW YORK, N. Y.

ADJUSTER FOR SUPPORTING LEGS

Application filed December 6, 1930. Serial No. 500,479.

This invention relates to adjusting and leveling devices adapted to be attached to supporting legs such as the legs of tables or cabinets and, more particularly, to such devices which may be attached to the bottom of such legs without trimming or otherwise marring the legs and having one member fixedly secured to the bottom of the leg with which the device is used.

10 One of the objects of the invention is to provide a leveling device comprising a cylindrical, exteriorly threaded member, a cooperating, interiorly threaded member rotatably engaging therewith to effect relative vertical movement between the members, and to provide means for fixedly securing the exteriorly threaded member to the bottom of a table leg or the like.

15 Another object is to provide a leveling device as described and to also provide a protector cap adapted to be secured to the exteriorly threaded member and having a skirt portion providing an interior opening in the cap for receiving the interiorly threaded cooperating member.

20 Another object is to provide a leveling device as described, in which the exteriorly threaded member is provided with a vertically extending groove and the interiorly threaded member is provided with a plunger, the groove being provided with a side wall of increasing depth with which the plunger cooperates to limit the relative vertical movement of the two members.

25 Another object is to provide such a leveling device in which the outer cooperating member is provided with a convex lower face to facilitate turning of said member and

30 movement of the article to which the device is attached.

35 With the above and other objects in view, my invention consists in the parts, improvements and combinations more fully pointed out hereinafter.

40 Referring to the drawing which illustrates embodiments of the invention:

45 Figure 1 is a vertical section showing the device attached to the bottom of a supporting leg.

Figure 2 is an inverted horizontal section on the line 2—2 of Figure 1,

Figure 3 is an inverted horizontal section on the line 3—3 of Figure 1,

Figure 4 is an elevation, partly in section, of a modified form of leveling device attached to a leg. 55

Figure 5 is a bottom plan view of the device shown in Figure 4, and

Figure 6 is a perspective view of the leveling device showing the protector cap secured to the inner member. 60

The construction shown provides means whereby the device may be attached to the bottom of a leg without trimming or otherwise marring the leg and also provides means whereby one of a pair of screw-threaded cooperating members can be fixedly secured to the bottom of the leg. 65

The device is shown attached to the bottom of a leg 1, and comprises a hollow cylindrical member 2, the upper end of which terminates in an inwardly turned annular flange 3, adapted to provide an opening at 4. Member 2 is adapted to be fixedly secured to the bottom of the leg 1. In the form shown a screw is provided to effect this result. The shank 5 of the screw passes thru the opening at 4, and takes into the bottom of the leg 1. The screw carries 70 means engaging the underside of flange 3. The headed end of the screw may engage the flange to fix the member 2 to the table leg, or, as shown, washers 6 may be interposed between the screw head and the flange. 75 Carried on member 2, is a cooperating member 8, provided with a central bore which is interiorly threaded at 8a to engage with the exterior threads 7 of member 2. Member 8, thus rotatably engages member 2, and the 80 rotation of this member effects relative vertical movement between the members. 85

Means are provided for protecting the working parts of the device.

As illustrated, a protector cap is provided 90 for the working parts, comprising a horizontal body portion 10, having a central opening, the wall of which is interiorly threaded to engage the exterior threads 7 of the member 2. The protector cap is also provided 100

with an annular skirt portion 12 forming the wall of a recess within which the cooperating member 8, operates.

The exterior threading of member 2 and interior threading of member 8 enables several advantages, in a device of this nature, to be secured, and the protector cap for the working parts improves the results obtained. It will be seen that the device has no exposed exterior screw threading. Such exposed threading is objectionable for if the threads extend thruout the length of the members, a number of sharp edges are exposed upon which clothing may catch and to which portions of cleaning rags or mops may adhere to cause binding of the parts. On the other hand, if the threads, to reduce such faults, do not extend for a considerable portion of the length of the member, then the adjustment range is considerably curtailed. The construction herein described avoids binding as by collection of dust or other foreign matter, has no exposed threads upon which clothing may be caught, and is provided with a protector cap which avoids the collection of dust upon the parts.

Means are provided for securing the protector cap to the exteriorly threaded member 2, to prevent their relative rotation. These means are also utilized to assist in fixedly securing both members to the bottom of a supporting leg.

As shown, the upper face of the horizontal portion 10 of the cap and the flange 3, of member 2, after these parts are assembled together, are centerpunched as shown at 13. This operation provides a firm union between the cap and member 2 and prevents their relative rotation.

The raised points of metals, shown at 14, resulting from the center-punching can be pressed into the bottom of a table leg to assist in fixedly securing the cap and the exteriorly threaded member to the leg.

Means are provided for limiting the relative vertical movement between members 2 and 8, so as to prevent member 8 from becoming completely disengaged from member 2.

As shown, member 2 is provided with a vertical groove 15. This groove is cut to incline downwardly and inwardly and is also cut to incline inwardly toward the center, thus providing the groove with a side wall 15a the depth of which increases downwardly along member 2. Cooperating member 8 is provided with a horizontal passage which extends from the central bore to the outer face thereof. Carried in this passage is a plunger 16, adapted to be pressed into the groove by a spring 17 and set screw 18. As member 8, is turned to cause members 8 and 2 to move apart, plunger 16 is spring pressed more deeply into the deepening groove 15, until near the lower end of the groove it is

held by the increased depth of the side wall 15a and further movement of the members in a direction apart from each other, is prevented. Conversely, member 8, can be rotated to cause relative movement between members 2 and 8, in a direction toward each other, without hindrance, the plunger, upon such rotation, being pressed back, compressing the spring, and moving out of the groove, and encountering less depth of side wall 15a. By this construction member 8 is at all times mounted upon member 2 and cannot become completely disengaged therefrom.

Means are also provided for facilitating the movement of the article from place to place and for decreasing the resistance offered by the floor to such movement.

In the form shown in Figures 1 to 3, the lower face 19 of the member 8 is convex, which enables the article to which the device is attached to be easily slid from place to place without marring the floor, while in Figure 4, the lower face 21 of a cooperating member 20 is convex and is provided at 22 with a central opening within which a ball bearing 23 is contained. This construction further decreases the resistance offered by the floor and enables the article to which the device is attached to be easily rolled from place to place without marring the floor or the covering thereon.

Having thus described the construction, its assembly and operation will be clear. Before the device is attached to a leg the protector cap is threaded on the member 2 and the cap and member are centerpunched as described herein to join the two together and prevent their relative rotation. The shank of the screw is then passed thru the opening in member 2 and forced upwardly thru the bottom of the leg, while the raised points of the centerpunched portion are also pressed into the table leg, to fixedly secure the cap and member 2 to the bottom of the leg. Cooperating member 8 is then threaded on cylindrical member 2. This completes the assembly and attachment of the device to a supporting leg. Thereafter, it is only necessary to rotate member 8 to bring about relative vertical movement between members 2 and 8, and thus effect the desired adjustment of the article.

What I claim is:

1. An adjuster for supporting legs comprising a cylindrical, exteriorly threaded member, a cooperating, interiorly threaded member rotatably engaging therewith for effecting relative vertical movement between the members, an exterior vertical groove in said exteriorly threaded member, said groove having a side wall increasing in depth toward the lower end of the member, a spring pressed plunger carried by said cooperating member adapted to engage said side wall

and limit the relative vertical movement of said members, and means for securing the exteriorly threaded member to the bottom of a supporting leg.

- 5 2. An adjuster for supporting legs comprising a cylindrical, exteriorly threaded member, a cooperating interiorly threaded member rotatably engaging therewith, a protector cap adapted to be threaded on said
- 10 exteriorly threaded member, means for locking said cap and exteriorly threaded member together, a skirt portion on said cap extending about said exteriorly threaded member and its cooperating member, and
- 15 means for fixedly securing the exteriorly threaded member to the bottom of a supporting leg.
- 3. An adjuster for supporting legs comprising a cylindrical, exteriorly threaded
- 20 member, a cooperating, interiorly threaded member rotatably engaging therewith for effecting relative vertical movement between said members, a protector cap adapted to be threaded on the exteriorly threaded mem-
- 25 ber and to be locked thereto, a skirt portion on said cap extending about said members, means for limiting the relative vertical movement of said members, and means for fixedly securing the exteriorly threaded
- 30 member to the bottom of a supporting leg.

In testimony whereof, I have signed my name to this specification.

JOHN J. PETERS.
